SAFETY GATE FOR PROJECTILES

William J. Flett, Washington, D. C., assignor to
the United States of America as represented by
the Secretary of the Navy

Application January 26, 1943, Serial No. 473,649

1 Claim. (Cl. 102—70)

1

This invention relates to safety devices for explosive projectiles of the rotary type and has particular reference to a novel safety device for preventing premature explosion of the projectile through the firing train and which remains in an unarmed or safe position until it has been acted upon by the dual forces of setback and centrifugal force incident to firing the projectile from a gun.

One object of the invention is to provide a novel safety gate in the firing train of a projectile fuze, in which the gate element is normally locked in its safe or unarmed position until the device is acted upon successively by a force of setback and an opposing force, such as set forward. In the new device, the gate element is normally locked in its safe position by means of a pin slidable in the gate under the force of setback when the projectile is fired, the pin being secured against movement from its locking position, preferably by means of a spring. In one form of the device, the spring is in the form of a collar on the locking pin, and when the device is subjected to a force of setback, the collar is displaced from the pin so that the latter is movable by a force set forward to a position for releasing the gate. In another form of the invention, the spring normally maintains the locking pin in its operative position and is distorted to accommodate movement of the pin to an inoperative position by explosion of a detonating cap which is fired by the force of setback of the pin. When the pin releases the gate, the action of centrifugal force on the gate moves it outwardly to unblock the firing train.

Another object of the invention is to provide a novel safety gate in which the gate element remains in its safe or unarmed position despite rough treatment, such as dropping or tumbling the projectile.

These and other objects of the invention may be better understood by reference to the accompanying drawing, in which

Fig. 1 is a side view of a projectile embodying one form of the new safety device, with part of the projectile casing broken away to show the device;

Fig. 2 is an enlarged transverse sectional view of the device shown in Fig. 1;

Fig. 3 is a sectional view of the line 3—3 in Fig. 2;

Fig. 4 is a view similar to Fig. 3 showing the position of the locking pin after it has been subjected to a force of setback;

Fig. 5 is a view similar to Fig. 4 showing the

locking pin after it has been subjected to a force of set forward; and

Fig. 6 is a longitudinal sectional view of part of a modified form of the device.

Referring to the drawing, the numeral 10 designates a projectile containing an explosive charge 11 and a booster unit 12 embedded in the charge. The booster is threaded into a recess 13 in the rear end of a body 14 which houses the parts of the safety device. At its front end, the body 14 is externally threaded, as shown at 14a, and is screwed into the rear end of a can 15 containing the parts of a fuze (not shown).

In the front end of the body 14 is a recess 16 for receiving a squib holder 17 which may be secured in the recess in any desired manner. An axial port or bore 18 extends between the recess 16 and the socket 13 for causing an explosion in the squib holder to detonate the booster 12.

20 In the bottom of recess 16 is a central elongated slot 19 which is relatively shallow near the port 18 so as to define a shoulder 20, the slot 19 intersecting the port 18 to the rear of a squib 21 disposed in a recess 21a in the rear face of the holder

25 17. An elongated gate element 22 is slidably mounted in the slot 19 and is provided on its rear face with a shoulder engageable with the shoulder 20 for limiting inward movement of the gate. When the gate is in its innermost position, as 30 shown in Figs. 2, 3 and 4, it blocks the port 18 so as to prevent firing of the booster 12 by accidental explosion of the squib 21.

In order to lock the gate 22 in its innermost or safe position, I provide a detent pin 23 extending through an opening in the outer portion of the gate and projecting rearwardly into a socket 24 in the body 14. The front end portion of pin 23 projects from the gate and has an annular groove for receiving a spring collar 25 normally seated on the front face of the gate, the collar and the front end of the pin being disposed in a recess 26 in the rear face of the squib holder 17. A socket 27 in the holder 17 communicates with the recess 26 and is disposed in line with the

40 front end of locking pin 23.

45 When the projectile is fired from a gun the force of setback moves pin 23 rearwardly into socket 24, thereby forcing the spring collar 25 off the front end portion of the pin. The collar

25, when it is released from the pin, moves outwardly in recess 26 (Fig. 4) under the action of centrifugal force incident to rotation of the projectile. Thereafter, the force of set forward following deceleration of the projectile moves the pin 23 forwardly through the gate 22 into the

socket 27 so as to release the gate. The gate 22 is then shifted outwardly in recess 19 by centrifugal force to clear the port 18, as shown in Fig. 5, whereby the squib 21 is adapted to explode the booster in recess 13 through the discharge port 18.

The modified construction shown in Fig. 6 is generally similar to that shown in Figs. 2 to 5, inclusive, except that the gate 22 is normally locked in its safe position by a pin 23a which is urged by a coil spring 29 against an explosive cap 30 disposed in the socket 24. The spring 29 is seated at one end in a recess in the pin 23a and at its opposite end on the bottom of socket 27. In the operation of this form of the device, the force of setback incident to firing the projectile from a gun causes the pin 23a to move rearwardly and explode the cap 30, whereupon the pin is moved forwardly against spring 29 into the socket 27. Accordingly, the gate 22 is released and moves outwardly in recess 19 under the action of centrifugal force to unblock the squib discharge passage 18.

The new safety device provides an effective means for preventing premature detonation of a projectile fuze. Since the pin 23 can move rearwardly into the socket 24 only when acted upon by a force of setback, it cannot be easily

dislodged by rough handling. Also, the gate 22 is finally released from its safe position only after the spring collar 25 has been removed by a force of setback and the pin 23 has moved into socket 27 by a force of forward set.

I claim:

A safety device for projectiles, comprising a gate movable between operative and inoperative positions, a member normally locking the gate in its operative position, the member being movable in one direction in the gate by a force of setback and in the opposite direction in the gate to release the gate, and an explosive device mounted at one end of said member and operable by a force of setback on the member to move the same in the direction for releasing the gate.
